UNITED STATES PATENT OFFICE.

WILLIAM M. RUTAN, OF ROOSEVELT, NEW YORK, ASSIGNOR TO GILLIS & GEOGHEGAN, INC., OF NEW YORK, N. Y., A CORPORATION OF NEW YORK.

HOISTING MECHANISM.

Application filed April 19, 1923. Serial No. 633,040.

To all whom it may concern:

Be it known that I, WILLIAM M. RUTAN, a citizen of the United States, residing at Roosevelt, in the county of Nassau and 5 State of New York, have invented a certain new and useful Improvement in Hoisting Mechanism, of which the following is a specification.

The invention relates to electrically 10 operated hoisting machines and more especially to machines for raising ash-cans and like light loads from the cellar to the sidewalk. The present invention is based on the mechanism shown and described in Letters Patent to Joseph H. Donat for an improvement in hoisting mechanism, dated March 9, 1920, No. 1,333,064, in which the hoisting, lowering, and braking operations are all controlled by a single operating-lever 15 swung to different positions.

The object of the invention is to provide means for automatically and positively controlling the brake by direct action through the operating-lever instead of relying upon 20 the action of a spring to apply the brake, thus eliminating the work required in overcoming the force of such spring in releasing the brake, and also avoiding the danger of accident due to failure of such spring in a 25 hoisting operation.

The invention consists in certain details of construction and arrangement by which the above objects are attained, to be herein-after described and claimed.

30 The accompanying drawings form a part of this specification and show the invention as it has been carried out in practice.

Figure 1 is a side elevation of a hoisting head and a portion of the electric motor 35 mounted thereon, partially in vertical section, and with portions of the frame broken away to show the parts beyond.

Figure 2 is a corresponding view of a portion of the opposite side of the head.

40 Figure 3 is a plan view of the brake-lever with its operating wing shown in horizontal section.

Figure 4 is a section taken on the line 4-4 in Figures 1 and 3 and partly in elevation.

45 Figure 5 is a vertical section on a larger scale, taken on the line 5-5 in Figure 1 and partly in elevation.

Similar reference numerals indicate the 50 same parts in all the figures.

The horizontally disposed frame of the hoisting head is marked 5 and is adapted to be mounted on a standard, not shown, which may be understood to be as usual and equipped with means for elevating and 60 lowering such head. In the frame is mounted the transversely extending hoisting shaft 6 having keyed thereon adjacent one of its bearings the hoisting drum 8 which is also keyed to a beveled gearwheel 42; a similar 65 gearwheel 43 oppositely disposed has a sleeve 44 on which is keyed the brake-drum 7 adjacent the other bearing for the shaft 6. An annular wormwheel 48 encircles the shaft between the beveled gearwheels 42 and 70 43 and carries radial arms 45, only one of which is shown, on each of which is mounted a beveled pinion 46 in mesh with both the beveled gearwheels 42 and 43, and the teeth of the wormwheel 48 mesh with the 75 worm 9. The beveled gearwheels 42 and 43 with the pinions 46 form a differential gear and operate in the manner usual in such mechanism. The worm 9 is driven by the motor shaft 10 of an electric motor 23 in 80 axial alinement therewith and equipped with a magnetic brake indicated at 47, of the usual construction, actuated by a switch, not shown, in a controller-box 22.

A brake lever 12 fulcrumed to the frame 85 at 13 carries the brake-band 11 and is arranged to tighten the band and apply the brake by a depression of its free end, and to release the brake-drum by a lifting movement of such free end.

90 Mounted in the frame is a transversely extending operating shaft 14 carrying on its overhung end the boss 15 of a depending operating lever 16 by which the shaft 14 is oscillated. Between the boss 15 and the frame is a collar 17 loosely mounted on the shaft, having a radially projecting arm 18 connected by a link 19 to a crank arm 20 on the controller shaft 21 extending into the controller box 22 and operating the electric 95 switch therein to control the current to the motor 23 and its magnetic brake 47 as usual. The arm 18 carries a lug 24 in the path of the operating lever 16 when the latter is 100 swung to the left in Figure 2, by which engagement the controller shaft 21 is partially turned to energize the motor and raise the load, and when released by a movement of the lever 16 to the right, is automatically 105 returned to the neutral position by the usual 110

spring actuated mechanism within the controller box 22. In this position the current is cut off and the magnetic brake 47 energized to hold the motor shaft 10 stationary, and the arm 18 carries the lever 16 with it by the action of the lug 24 thereon in such return movement when the lever is free.

At the opposite end of the operating shaft 14, within the frame, is fixed a boss 25 having a radially disposed wing 26 thereon, notched as at 27 to form fingers 28.

The rear end of the brake lever 12 extends beneath the boss 25 and its wing 26 and is provided with a wide platform 29 curved on its upper face concentrically to the axis of the operating shaft 14 on an arc described by the extremities of the fingers 28. At the rear the platform is upturned to form a ledge 30 serving as a stop for the fingers in their sweep in that direction, and at the front the platform is curved downwardly and forwardly as at 31 to lead the fingers smoothly to the concentric portion of the platform. The part 31 overhangs a deep recess 32 in the lever and is notched at 33 at the front.

The bottom of the recess is formed by a boss 33 on the lever, through which extends a screw 34 standing approximately vertically and provided with nuts 35 placed above and below the boss 33 by which the screw may be adjusted as to height relatively to the lever. The screw extends through the notch 39 provided for that purpose. At the upper end of the screw is a cylindrical cross-bar 36 disposed transversely of the lever and having a rectangular notch 37 on its front matching and engaged with a flanged way 38 on the lever, serving as a guide for the cross-bar and insuring its transverse relation to the lever in all positions of vertical adjustment.

The cross-bar is arranged to be struck by the fingers 28 and lifted by the latter, thus raising the free end of the lever and releasing the brake.

From the boss 15 of the operating lever 16 extends a lateral arm 40 carrying an adjustable counterweight 41 serving to hold the operating lever normally in contact with the lug 24 and in the vertical or neutral position in which the fingers 28 are engaged with the platform 29 and the brake applied. The force exerted by the counterweight is sufficient to effect such contact of the lever with the lug but not great enough to overcome the resistance offered by such lug due to the spring, not shown, in the controller box 22 acting upon the controller shaft 21 in the usual manner.

The operation is as follows:—Assuming the parts to be in the positions shown in the figures, which is the neutral position, and a load to be hoisted, the operating shaft 14 is oscillated by swinging the operating

lever 16 to the left in Figure 2, carrying the arm 18 with it and through the link 19 and crank arm 20 turning the controller shaft 21 to supply current. The fingers 28 on the opposite end of the operating shaft 70 by their contact with the platform 29 hold the brake lever 12 depressed and maintain the grip of the brake band 11 on the brake drum 7. The latter with the beveled gear-wheel 43 are thus held stationary and the rotation of the worm 9 in turning the worm-wheel 48 causes the pinions 46 to rotate and thus turn the beveled gearwheel 42 and hoisting drum 8 with the shaft 6 in the direction to wind the cable, not shown, and raise the load. On releasing the operating lever 16 it is automatically returned to the vertical or neutral again, the current broken, and the magnetic brake 47 actuated, and as the brake drum 7 is still gripped the 75 load will remain suspended.

In lowering the load the operating lever is swung to the right in Figure 2, away from the arm 18 which is left in the neutral or inoperative position, and the fingers 28 80 sweep over the curved surface of the platform 29 until they strike the cross-bar 36 on the brake lever 12 and raise the free end of the latter to slacken the brake band 11 and release the brake drum. In this condition the weight of the load revolves the hoisting drum 8 in the reverse direction and the load lowers by gravity, its speed of travel being controlled by slight movements of the operating lever to tighten or loosen 85 the brake band. In the lowering operation the hoisting shaft may revolve idly with the hoisting drum until arrested by the tightening of the brake band which, through the differential, stops such rotation. 90

It will be noted that the brake is operated directly and positively by the movements of the operating lever, and the disadvantages of spring-operation are avoided.

I claim:—

1. In a hoisting mechanism of the character set forth, a brake-drum, a brake-band thereon, a brake-lever for controlling said band, an operating shaft and means on said shaft arranged to act directly and positively 115 upon said lever for holding the latter in position to maintain the application of the brake during a portion of the oscillation of said shaft in one direction, and to release such brake directly and positively by a 120 continuation of such oscillation in the same direction.

2. In a hoisting mechanism of the character set forth, a brake-drum, a brake-band thereon, a brake-lever for controlling said band, an operating shaft, a platform on said lever concentric to said shaft, a bar on said lever, and a wing on said shaft arranged to contact with said platform and hold said lever in position to maintain the application of 130

the brake during the traverse of said wing along said platform, and to engage said bar at the end of such traverse and move said lever to release the brake.

5 3. In a hoisting mechanism of the character set forth, a brake-drum, a brake-band thereon, a brake-lever for controlling said band, an operating shaft, a platform on said lever concentric to said shaft, a bar on 10 said lever at one end of said platform, a wing on said shaft arranged to contact with said platform and hold said lever in position to maintain the application of the brake during the traverse of said wing along said 15 platform, and to engage said bar at the end of such traverse and move said lever to release the brake, and means for adjusting the position of said bar.

4. In a hoisting mechanism of the char-

acter set forth, a brake-drum, a brake-band 20 thereon, a brake-lever for controlling said band, an operating shaft, a platform on said lever concentric to said shaft, a bar on said lever at one end of said platform, a stop at the other end of said platform, a wing on 25 said shaft arranged to contact with said platform and hold said lever in position to maintain the application of the brake during the traverse of said wing along said platform in one direction, and to engage 30 said bar and move said lever to release the brake by a continuation of such traversing movement, and again to contact with said platform in a traverse in the opposite direction limited by said stop.

In testimony that I claim the invention above set forth, I affix my signature hereto.

WILLIAM M. RUTAN.
